CLAIM

The ornamental design for an anchor member for a support bracket for poles, as shown and described.

DESCRIPTION

FIG. 1 is a bottom and rear perspective view of an anchor member for a support bracket for poles showing my new design;

FIG. 2 is a top plan view thereof, the bottom being identical;

FIG. 3 is a front elevational view thereof;

FIG. 4 is a side elevational view thereof; the other side being identical;

FIG. 5 is a rear elevational view thereof;

FIG. 6 is a bottom and rear perspective view, showing the second embodiment of the design in FIG. 1;

FIG. 7 is a top plan view of FIG. 6, the bottom being identical;

FIG. 8 is a front elevational view of FIG. 6;

FIG. 9 is a side elevational view of FIG. 6, the other side being identical; and,

FIG. 10 is a rear elevational view of FIG. 6.
